No. 665,257.

Patented Jan. 1, 1901.

H. W. & M. W. McDONALD.

SEWER INLET.

(Application filed Mar. 24, 1899.)

(No Model.)

UNITED STATES PATENT OFFICE.

HIRAM W. McDONALD, OF GALION, OHIO, AND MOTT W. McDONALD, OF ROCHESTER, NEW YORK.

SEWER-INLET.

SPECIFICATION forming part of Letters Patent No. 665,257, dated January 1, 1901.

Application filed March 24, 1899. Serial No. 710,333. (No model.)

To all whom it may concern:

Be it known that we, HIRAM W. McDONALD, of Galion, Ohio, and MOTT W. McDONALD, of Rochester, New York, citizens of the United States, have invented certain Improvements in Sewer-Inlets, of which the following is a specification, reference being had to the accompanying drawings.

Our invention relates to certain improvements in the construction of sewer-inlets, which improvements are fully described and illustrated in the following specification and the accompanying drawings, the novel features thereof being specified in the claims annexed to the said specification.

In the accompanying drawings, representing our improvements in sewer-inlets, Figure 1 is a plan view. Fig. 2 is a front elevation. Fig. 3 is an end view. Fig. 4 is a front view of the grate. Fig. 5 is an end view of the same. Fig. 6 is a plan view of the same. Fig. 7 is a section on the line 7 7, Fig. 3. Fig. 8 is a section on the line 8 8, Fig. 1.

In the accompanying drawings, A represents the body, which is open at top and provided on its lower side with a suitable ring or pipe connection B.

C is the adjustable curb-section.

D is the adjustable grate, and E the perforated gutter-grate.

The curb-section is closed on the top and sides except that it has an opening toward the street, which opening is crossed by the adjustable grate D. The curb-section is narrower than the body, and the space in the top of the body in front of the section is occupied by the perforated gutter-grate E. The ends of the curb-section are slotted, as indicated at F, Fig. 3, and the bolts and nuts H are employed to hold the curb-section in any desired position of adjustment relatively to the body. This adjustment is indicated by the full and dotted lines in Figs. 2 and 3. The construction also admits of the curb-section

being inclined outward or inward, as indicated 45 by the dotted lines in Fig. 3.

I represent the curbstones set at each end of the inlet.

The grate D is of any suitable construction, being preferably made of wrought-iron. At 50 each end the grate is provided with the heads J, having slots L, Fig. 5, which correspond with the slots F in the ends of the curb-section, so that both the section and the grate may be held in place by the same bolts H. Provision 55 is thus made for adjusting the curb-section and grate relatively to each other or with relation to the body.

The gutter-grate E is provided at one end with the projecting lug N, which enters an 60 opening in the end of the body, and at the other end with a perforated lug P, Fig. 8, into which the pin Q is inserted, so as to hold the grate in place. Outside the pipe connection B the bottom of the body is inclined upward, 65 as indicated by the dotted lines T, Fig. 2, so as to prevent the accumulation of mud or sediment. The sides and ends, however, are continued downward, and a web U, Fig. 3, may extend down from the inclined bottom 70 plates T. In this way a square base is given to the body, so that it may be firmly supported by the masonry.

We claim—

1. A sewer-inlet comprising an adjustable 75 curb-box, and an adjustable and removable grate in the front of the curb-box.

2. In a sewer-inlet, the combination with the hollow body, of the adjustable curb-section open on the front side and the adjustable 80 grate placed across the opening in the section, as and for the purposes set forth.

3. In a sewer-inlet, the combination with the hollow body, of the adjustable curb-section open on the front side, the adjustable 85 grate across the opening in the section, and the removable gutter-grate, as and for the purposes set forth.

4. In a sewer-inlet, a hollow body with an open curb-section, a grate in the curb-section, and means for securing the grate and curb-section in adjusted position relative to each other and to the body.
5. In a sewer-inlet, the combination of the hollow body with the adjustable open curb-section and the adjustable grate across the opening in the section each provided with ¹⁰ corresponding vertical slots in their ends, and means for securing the section and grate in any desired position relatively to each other

and the body, as and for the purposes set forth.

HIRAM W. McDONALD.
MOTT W. McDONALD.
